(57) **CLAIM**

The ornamental designs for coiled strip of closures, as shown and described.

DESCRIPTION

FIG. 1 is a top perspective view of a coiled strip of closures of the design of the present application;

FIG. 2 is a top view of the design of FIG. 1;

FIG. 3 is a bottom view of the design of FIG. 1;

FIG. 4 is an elevational view of the design of FIG. 1;

FIG. 5 is an elevational view of the design of FIG. 1 taken from the opposite side of the design relative to FIG. 4;

FIG. 6 is a side elevational view of the design of FIG. 4 taken 90 degrees from the view of FIG. 4;

FIG. 7 is a further elevational view of the design of FIG. 1 taken from the opposite side of the design relative to FIG. 6. FIG. 8 is a top perspective view of a coiled strip of closures of a second embodiment of the present application with portions shown in broken lines;

FIG. 9 is a top view of the design of FIG. 8;

FIG. 10 is a bottom view of the design of FIG. 8;

FIG. 11 is an elevational view of the design of FIG. 8;

FIG. 12 is an elevational view of the design of FIG. 8 taken from the opposite side of the design relative to FIG. 11;

FIG. 13 is a side elevational view of the design of FIG. 8 taken 90 degrees from the view of FIG. 11; and,

FIG. 14 is a further elevational view of the design of FIG. 1 taken from the opposite side of the design relative to FIG. 13. The broken lines in FIGS. 8-14 depict unclaimed environmental subject matter and form no part of the claim.

1 Claim, 6 Drawing Sheets
